SPECTROMETER CONSOLE

Ronald E. Haynes, Palo Alto, and Hugh J. Hall, Los Altos, Calif., assignors to Varian Associates, Palo Alto, Calif., a corporation of California

Filed Feb. 20, 1961, Ser. No. 64,000

Term of patent 14 years

(Cl. D26—5)

FIG.1

FIG.2

FIG.3

FIG.4

FIG. 1 is a perspective view of a spectrometer console showing our new design;

FIG. 2 is a front elevational view thereof;

FIG. 3 is a side elevational view thereof, the opposite side being substantially a mirror image; and

FIG. 4 is a plan view thereof.

We claim:

The ornamental design for a spectrometer console, as shown and described.
